(57) **CLAIM**

The ornamental design for a hitch assembly, as shown and described.

DESCRIPTION

FIG. 1 is a perspective view of a hitch assembly, showing my new design.

FIG. 2 is a left side view of the hitch assembly of FIG. 1. FIG. 3 is a right side view of the hitch assembly of FIG. 1. FIG. 4 is a front view of the hitch assembly of FIG. 1. FIG. 5 is a rear view of the hitch assembly of FIG. 1. FIG. 6 is a top view of the hitch assembly of FIG. 1; and, FIG. 7 is a bottom view of the hitch assembly of FIG. 1. The broken line portions of FIGS. 1-7 are included to show unclaimed subject matter only and form no part of the claimed design.
